Inventor:

Raymond D. Foltz,

By Constance, Miss Weston At 75.

UNITED STATES PATENT OFFICE

RAYMOND D. FOLTZ, OF SOUTH ORANGE, NEW JERSEY, ASSIGNOR TO M. H. DETRICK COMPANY, OF CHICAGO, ILLINOIS, A CORPORATION OF ILLINOIS

FURNACE CONSTRUCTION

Application filed May 4, 1929. Serial No. 360,335.

This invention relates to construction of furnaces of the types wherein the furnace chamber walls and roof, or parts thereof, are formed of refractory tiles, in order that they 5 may withstand high temperatures. It finds particular application in such furnace walls and roofs wherein the tiles or refractories are suspended or anchored on exterior supporting members.

10 A general object of the invention is the provision of an improved construction for furnace walls and arches, and a novel and advantageous refractory tile for use in the same, whereby both furnace walls and furnace roofs 15 may be constructed for the most part of tiles of a single size and form, with suitable provision for anchorage of the tiles in such manner as to retain them in the desired assembly in the structure yet permit them a proper degree 20 of individual movement for the accommodation of thermal expansion, while maintaining close joints effective to prevent flame leakage between juxtaposed tiles.

A specific object of the invention is the provision 25 of a special refractory tile which, because of its structural characteristics, is specially qualified to contribute the aforementioned advantages to furnace roofs and walls in which it is employed, and which is 30 adapted for manufacture economically and in quantities, without requiring special handling or treatment.

Another object is the provision of an improved construction for furnace roofs and 35 walls, and an improved refractory tile for forming same, whereby tight joints may be provided between juxtaposed tiles and at the same time the desirable latitude of fit allowed for accommodation of the variations in size 40 which are unavoidably encountered in the manufacture and installation of heavy and comparatively roughly formed structural elements such as in the construction of large furnaces.

45 Other and further objects will be pointed out or indicated hereinafter, or will become apparent to one skilled in the art upon an understanding of the invention or its employment in practice.

50 For the purpose of aiding in the disclosure

of the invention I illustrate in the accompanying drawing, forming part of this specification, certain examples of its embodiment, but it is to be understood that these are presented for purpose of illustration merely, and are not to be given any interpretation calculated to limit the claims short of the true and most comprehensive scope of the invention in the art.

55 In such drawing,

Fig. 1 represents a face view of an assembly 60 of one form of refractory tiles in accordance with my invention, which assembly may be taken as illustrative of their relationship in either a furnace roof or a furnace wall structure;

65 Fig. 2 is a sectional elevation of a portion of a furnace wall structure in which the invention may be embodied;

70 Fig. 3 is a sectional elevation of a portion of a furnace roof structure in which the invention may be embodied; and

75 Fig. 4 is an end elevational view of one of the tiles illustrated in Fig. 1.

80 For economy in the manufacture, installation and maintenance of furnaces, such as large boiler furnaces, metallurgical furnaces and other industrial furnaces, it is quite desirable that the refractories and other structural elements be standardized, or of uniform size and design, insofar as possible, and that such standardized parts be qualified for a wide variety or versatility of use, so that furnaces of great variety of design may be constructed or equipped by the use of such standardized parts. Due to the unavoidable variations 85 which occur in manufacture of such structural elements as refractories, iron castings, structural steel, concrete foundations and other elements entering into the construction of large furnaces, it is very difficult, with reasonable economy, to obtain in the assembly of the parts the precision and nicety of fit which may be the theoretical ideal. Consequently, it becomes important to include in such standardized structural elements compensating features whereby variations in size 90 may be accommodated and a proper fit obtained under varying conditions occurring 95 100

both in installation and operation of the furnaces.

The present invention provides an improved refractory tile construction and furnace arch and furnace wall construction whereby suitable tight joints between juxtaposed tiles may be obtained at installation and maintained incident to operation, in furnaces which may vary greatly in size, design and kind. By virtue of the special form which characterizes the tile, it is qualified for quantity production very economically without material wastage, adapted for installation with great facility and without requiring special skill, and is particularly qualified to withstand the forces occurring from mechanical pressures and thermal effects resulting from the nature of the furnace structure and its use.

The nature of the invention may be most quickly ascertained by consideration of the examples shown in the drawing. Referring to Fig. 2, it will be understood that the member designated by the reference numeral 10 is a tile engaging member in the nature of a bracket which forms an element of a furnace wall construction. Reference may be had to British Patent No. 238,724 of M. H. Detrick Company for an illustration of a manner in which such brackets may be employed for the anchorage of wall sections 11, made up of refractory tiles, said brackets being supported on a metallic framework, portions of which are indicated at 12. Likewise, by reference to Fig. 3, it will be understood that the member designated by the reference numeral 14 is a tile-retaining member in the nature of an arch bar for a furnace arch or roof portion, which arch bar may be suspended in a well known fashion from a supporting framework by means of hangers 15, and may be disposed in either a horizontal or sloping position, the refractory tiles 16 being suspended on said arch bar, face to face, so as to form a course, which constitutes a roof or arch section. In Fig. 1, the members designated by the reference numeral 17 are tile-retaining members which may be in the nature of either the member 10 or the member 14. These tile-retaining members are provided with tile engaging portions 17^a, here shown as marginal flanges, the purpose of which is to afford a retentive anchorage for the refractory tiles 18. These tiles are as nearly identical as the limitations of manufacture permit, and are formed of a refractory material such as fire clay, suitably burnt. They are formed at one end with a T-shaped slot 18^a adapted to accommodate the tile-retaining members and their tile engaging parts with a liberal clearance, so that the tile, while retained thereon, may have a certain latitude of both shifting and angular movement with respect to the tile engaging member. The T-shaped slot 18^a is centered on the median line between the

lateral faces 18^b and 18^c of the tile, which lateral faces are parallel. The offset side faces 18^d and 18^e are likewise parallel, both with respect to each other and with respect to the lateral faces 18^b and 18^c, but they are offset with respect to the latter so as to provide a projection at one side of the tile and a corresponding or complementary in-set at the other side. The faces 18^f between faces 18^b and 18^c on the one side, and 18^e and 18^f on the other side, extend obliquely to form bearing shoulders, the angle of which with respect to the lateral faces 18^b and 18^c is the same at both sides of the tile. The relationship of the bearing shoulders 18^f with respect to the slots 18^a and the lateral faces is such that when the anchorage lugs 18^g of the juxtaposed tiles are in alignment, their ends also will be in alignment. Consequently, when the tiles are placed together side to side with their ends in alignment, as illustrated in Fig. 1, the salient offset portion of one will overlap the reentrant offset portion of another and their juxtaposed bearing shoulders 18^f will be in abutment, but the faces 18^c and 18^f of one tile will be slightly spaced apart from the adjacent faces 18^b and 18^d of the other tile.

In the assembly of the furnace, the suitable tile-retaining members 17 being arranged in parallel collateral relationship, the requisite number of tiles 18 are slid onto the tile engaging portions, the tiles on the respective tile-retaining members thus being arranged in courses with their broader faces in abutment and the juxtaposed faces of tiles in adjacent courses slightly spaced apart, the intervening spaces being filled with a plastic refractory material, if desired. If in a wall construction, the courses will run upwardly, as illustrated in Fig. 2, and if in a roof, the courses will run in a horizontal or sloping direction, as illustrated in Fig. 3, and the bearing shoulders 18^f of tiles in juxtaposed courses will be in contact. Due to the play allowed for the tile-retaining members in the tile slots, individual tiles may accommodate their positions to laterally adjacent tiles so as to obtain the desired bearing contact of their bearing shoulders. Upon expansion of the tiles by heat, the contact of the bearing shoulders is maintained, the transverse expansion of the tiles being accommodated by the spaces between their lateral faces. When the tiles are suspended in a roof or arch, as typified in Fig. 3, the bearing engagement of the shoulders is maintained by the weight of the tiles. When they are disposed in an upwardly running course in a wall, as typified in Fig. 2, the bearing engagement of the shoulders is maintained by the expansion of the tiles, which expansion will be greater at their inner ends than at their outer ends, due to the fact that the inner ends are more highly heated. Accordingly, both at installation and in operation of the furnace,

the bearing shoulders of the juxtaposed tiles will be maintained in contact to form a close joint.

5 The tiles of this construction, in addition to affording the advantages above pointed out, are comparatively simple to manufacture, may be given uniform burn, and have adequate strength in their anchoring portions. They may be employed in numerous 10 varieties of furnace arch and wall constructions and may be made in various dimensions of length, width and thickness.

What I claim is:

1. An element for furnace construction 15 consisting of a refractory tile having its opposite side margins of complementary form and shaped at one side with a bearing shoulder offset diagonally outward and at the other side with a bearing shoulder offset diagonally inward, said side margins having 20 parallel faces conjoining the inner and outer ends of said diagonal bearing shoulders.

2. An element for furnace construction 25 consisting of a refractory tile having its opposite sides of complementary contour, said sides having parallel lateral faces for a part of their length and parallel oblique faces extending from said lateral faces, the oblique face at one side of the tile extending 30 outwardly from the adjacent lateral face and terminating at a side face of the tile which is out-set from that lateral face, the oblique face on the other side of the tile extending inwardly of the latter from the adjacent lateral face and terminating at a side face 35 which is in-set from said lateral face, said side faces being approximately parallel to said lateral faces, and the tile being provided with an anchoring slot adjacent one end.

40 3. In furnace construction, the combination with tile-retaining members, of refractory tiles loosely anchored thereon and disposed in collateral relationship, said tiles having their juxtaposed faces of complementary contour, the respective tiles having parallel lateral faces for a portion of their length and parallel oblique faces conjoining 45 said lateral faces, the oblique face at one side of the tile extending outwardly from the adjacent lateral face and terminating at a side face which is 50 out-set from the latter, the oblique face at the other side of the tile extending inwardly from the adjacent lateral face and terminating at a side face which is 55 in-set therefrom, the oblique faces of juxtaposed tiles being disposed in abutment and the tiles having anchoring slots accommodating the tile-retaining members.

In witness whereof I have hereunto 60 subscribed my name.

RAYMOND D. FOLTZ.
